(57) **CLAIM**

We claim the ornamental design for a vehicle lamp, as shown and described.

DESCRIPTION

FIG. 1 is a front perspective view of a vehicle lamp showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a left-side cross-sectional view thereof;

FIG. 9 is a right-side cross-sectional view thereof; and,

FIG. 10 is an enlargement of the encircled portion of the vehicle lamp shown in FIG. 2.

The broken lines in the drawing figures show portions of the vehicle lamp which form no part of the claimed design. The dot-dot-dash broken lines encircling portions of the claimed design that are illustrated in enlargements form no part of the claimed design.
